DESIGN FOR A BAG-GRASPING DEVICE

Alvan M. Palmer, Los Angeles, and Frederick
W. Rodgers, Pacoima, Calif.

Application April 26, 1946, Serial No. 128,965

Term of patent 14 years

(Cl. D54—13)

To all whom it may concern:

Be it known that we, Alvan M. Palmer and Frederick W. Rodgers, citizens of the United States, residing at Los Angeles and Pacoima, respectively, county of Los Angeles, and State of California, have invented a new, original, and ornamental Design for a Bag-Grasping Device, of which the following is a specification, reference being had to the accompanying drawing, forming part thereof.

Fig. 1 is a three-quarter front view of the bag-grasping device showing our new design.

Fig. 2 is a longitudinal section taken approximately along plane II—II of Fig. 1.

We claim:

The ornamental design for a bag-grasping device, substantially as shown.

ALVAN M. PALMER.
FREDERICK W. RODGERS.
